R. B. SOMERS AND T. OLINGER.

SPRING OILER.

APPLICATION FILED OCT. 27, 1919.

1,391,518.

Patented Sept. 20, 1921.

UNITED STATES PATENT OFFICE.

ROY B. SOMERS, OF ZEELAND, AND THOMAS OLINGER, OF HOLLAND, MICHIGAN,
ASSIGNORS TO FEDERAL STAMPING COMPANY, OF HOLLAND, MICHIGAN, A COR-
PORATION OF MICHIGAN.

SPRING-OILER.

1,391,518.

Specification of Letters Patent. Patented Sept. 20, 1921.

Application filed October 27, 1919. Serial No. 333,673.

To all whom it may concern:

Be it known that we, ROY B. SOMERS and THOMAS OLINGER, citizens of the United States of America, residing at Zeeland and 5 Holland, respectively, in the county of Ottawa and State of Michigan, have invented certain new and useful Improvements in Spring-Oilers; and we do hereby declare the following to be a full, clear, and exact 10 description of the invention, such as will enable others skilled in the art to which it appertains to make and use the same.

This invention relates to spring oiler, particularly adapted for application to leaf 15 springs of motor vehicles to supply the same with lubricant between the leaves thereof. It is an object and purpose of the present invention to construct a device of this character very simply and economically and 20 make the device readily applicable to leaf springs so that the same may be placed against the sides of the spring and supply lubricant to the springs at the sides thereof.

A still further object of the invention is to 25 construct this oiler whereby the same may be stamped from sheet metal so as to receive and hold an oil absorbing pad at one side, the construction thus made being adapted to be bent so as to apply to a leaf spring. A 30 still further object and purpose of the present invention is to equip the oiler with a lubricant receiving trough which will keep the lubricant from running down the upper side of the upper leaf of the spring. Various 35 other objects and purposes than those specifically stated will appear as understanding of the invention is had from the following description taken in connection with the accompanying drawing, in which:

40 Figure 1 is a side elevation of the oiler showing the same applied to a leaf spring which is shown in transverse section.

Fig. 2 is a fragmentary vertical section taken through the middle of the oiler and 45 adjacent parts of the spring.

Fig. 3 is a plan view of the device applied to a spring.

Fig. 4 is a section taken transversely of the oiler, substantially at its middle point.

50 Fig. 5 is a plan view of the telescoping trough member; and

Fig. 6 is a side elevation thereof.

Like reference characters refer to like parts in the different figures of the drawing.

In construction, a plate of thin sheet metal 55 1, relatively narrow in width, is provided which at its sides is formed with a consecutive series of triangular shaped projections 2 between which a pad 3 of felt or other absorbing material is placed and held. The 60 central portion of the plate 1 is raised forming a central cone 4 and a rib 4^a, as shown, the cone being provided with an opening 5 therethrough, through which the stem of an oil can may be inserted to supply the pad 65 with oil. In practice, this plate 1 with the pad attached is made in a single length and when it is to be applied to a spring, such as indicated at 6, it is placed against the upper side of the spring, and the ends bent downwardly so as to lie alongside the edges of the leaves as shown in Fig. 1. The plate 1 is provided with integral extending ends 7 having openings therethrough for the passage of a rod 8, the same being threaded at 75 one end to receive a nut for binding the device tightly against the spring 6.

This construction may absorb a considerable amount of oil and deliver the same to the leaf spring. In order to prevent the 80 flow of oil down the upper side of the upper leaf of the spring, a telescoping trough member is used, formed of two sections 9 and 10 which have upstanding sides 11 and 12 respectively, and downturned outer ends 13 85 and 14 respectively. The width of the trough member 10 is such that its sides 12 pass just inside of the projections 2 when placed against and under the pad 3. The member 9 is slightly narrower so that sides 90 11 of the same pass between the sides 12 of said member 10. This trough member is placed between the parts 2 which may, one or more of them, be bent inwardly to hold the trough in place and lies against the 95 spring. It is capable of being telescoped so that the down turned ears 13 and 14 bear against opposite edges of the upper leaf of the spring 6. The pad 3 lies within and against the bottom of trough members. This 100 prevents any loss of oil and requires that all of the oil must go to the down turned ends of the pad 3 from which it is transferred to and between the leaves of the spring.

This construction is made of thin sheet metal being quickly and readily stamped therefrom. It serves to keep the spring lubricated at all times. On account of the

shape of the projections 2 the member 1 may be bent at any point necessary for its application to a spring. The construction is simple and is very cheaply made and has 5 wide use to prove its serviceability.

We claim:

1. In combination with a leaf spring, a trough member comprising two telescoping parts located against the upper side of the 10 spring, a pad located in said trough member and extending downwardly at its ends so as to lie against the front and rear sides of the spring, a retaining member located over the pad and covering the same, and 15 means for applying oil to the pad through said retaining member, substantially as described.

2. In combination with a leaf spring, two telescoping trough members of sheet metal

located against the upper side of the leaf 20 spring, each of said members having a downturned outer end to limit the telescoping movement of the trough member when applied to the spring, a pad located in the trough member and turned downwardly at 25 its ends to lie against the front and rear sides of the spring, and a sheet metal retaining member lying over and against the pad and serving to secure it in position on the spring, said retaining member having triangular shaped projections turned at right angles at each side edge thereof and bearing against the side edges of the pad, substantially as described.

In testimony whereof we affix our signatures. 35

ROY B. SOMERS.
THOMAS OLINGER.
